VIBRATORY MOTOR DEVICE

Edward L. Barrett, La Grange, Ill., assignor to
 Utah Radio Products Company, Chicago, Ill.,
 a corporation of Illinois

Application October 12, 1936, Serial No. 105,297

7 Claims. (Cl. 200—90)

The invention relates generally to vibratory motor devices and more particularly to devices of this character which are especially well adapted for use as a circuit interruption means in electrical systems for transforming direct current into alternating current and thence into direct current, such systems for example being largely employed at present in providing electrical energy of proper potential for the operation of a motor 10 vehicle installation of a radio receiving set.

Such devices ordinarily include a vibratory reed driven by periodically energized electromagnet, the reed serving to open and close two or more main circuit controlling contacts. It has 15 heretofore been proposed to control the energization of the electromagnet by a separate set of driving contacts also operated by the vibratory reed. Arcing at the driving contacts has, however, been a serious problem in such devices, and 20 although various expedients have been proposed to eliminate such arcing, none of them, so far as is known, have proved to be completely effective in actual operation.

One object of the present invention is to provide a device of the type indicated having an electromagnet periodically energized through a circuit controlled by a pair of make and break driving contacts, the energizing winding of the electromagnet being of a novel form and of such 30 character as to minimize arcing at the driving contacts.

A more specific object of the invention is to provide in a vibratory motor of the type set forth a novel form of actuating electromagnet coil 35 adapted to minimize arcing at the driving contacts and embodying a conductive sheath surrounding substantially throughout its length the wire making up the coil or winding of the electromagnet but insulated therefrom.

40 Further objects and advantages of the invention will become apparent as the following description proceeds and the features of novelty which characterize the invention are pointed out with particularity in the claims annexed to and 45 forming a part of this specification.

For a better understanding of the invention, reference may be had to the accompanying drawing, in which:

Figure 1 is a perspective view on a reduced 50 scale of a vibratory motor device embodying the features of the invention, the enclosing case therefor being shown in broken outline.

Fig. 2 is an enlarged longitudinal sectional view of the vibratory motor assembly shown in 55 Fig. 1.

Fig. 3 is an exploded perspective view of the vibratory motor shown in Fig. 1.

Fig. 4 is a wiring diagram illustrating the connections from the vibratory motor device to its associated apparatus.

Fig. 5 is an enlarged fragmentary detail view of 5 a conductor included in the energizing winding of the vibratory motor electromagnet.

For purposes of illustration, the invention has been shown as embodied in a vibratory motor 10 particularly adapted to meet the exigencies of use in an automobile radio receiving set, although it is susceptible of a variety of other uses. In general, the vibratory motor includes two pairs of main circuit controlling make and break contacts 10—11 and 12—13, and a pair of driving contacts 14—15, all operated by a vibratory reed 16 which is driven by an actuating electromagnet 17.

In the preferred construction illustrated, the various parts of the vibratory motor are assembled on a rigid frame designated generally by the numeral 18. This frame is preferably of one-piece construction which includes a part for supporting the reed and contacts and another part constituting the core of the winding, these parts 25 all being located substantially on the same plane. Such a frame may be readily stamped or otherwise formed from a flat sheet of metal stock such as cold rolled steel. The latter material is suggested as it is desirable that the frame have a high magnetic 30 permeability. Referring particularly to Fig. 3, it will be seen that the frame 18 is of generally rectangular shape and includes end members 19 and 20 joined by side members 21 and 22. A projection 23 on the end member 19 forms a 35 core for the electromagnet 17. The side members 21 and 22 are offset somewhat from the plane of the end members in order to facilitate inspection and adjustment of the contacts after the device is assembled.

The reed 16 is of the cantilever type and is adapted to flex substantially throughout its length, being preferably made of spring steel or bronze. An elongated opening 24 is formed in the center of the reed in order to give it certain 45 preferred flexing characteristics and also to insure unimpeded flexure of the reed despite the multiplicity of associated contacts as is herein-after described in great detail. Upon reference to Fig. 3, it will be seen that the opening 24 increases in cross section adjacent the outer end of the reed, thereby providing a greater flexure in that portion. A rectangular armature 25 made of steel or other material having a high magnetic 50 permeability is spot welded or otherwise rigidly 55

secured to the free end of the reed. This armature is disposed in driven relation with respect to the pole piece 23 of the electromagnet 17.

The movable contact points 11 and 13 of the 5 respective pairs of main driving contacts are carried by the reed 16 intermediate its ends and are preferably positioned substantially in the plane of the reed in order to interfere as little as possible with its normal vibratory characteristics. 10 These contact points 11 and 13 are secured to contact supports 26 and 27 respectively, made of current conducting metal stock, these supports being in turn carried by the reed 16 to which they are securely fastened by rivets passing through 15 holes 28. It will be noted that the supports 26 and 27 span the opening 24 so that the contact points 11 and 13 are disposed in alinement with the opening.

Relatively fixed contact points 10 and 12 are 20 disposed on opposite sides of the reed 16 and cooperate with the movable contact points 11 and 13 to periodically open and close the associated electrical circuits upon vibration of the reed. A pair of sheet metal fingers 29 and 30 support 25 the contact points 10 and 12 in spaced relation with respect to their associated movable contacts when the reed 16 is in its idle position. It will be noted that the fingers 29 and 30 are provided with enlarged base portions 31 and 32 respectively, having terminal lugs 33 and 34 thereon. These bases also include integral laterally extending assembly lugs 35 and 36 projecting from the lower edges thereof. In the assembly of the 30 device, these lugs cooperate with a suitable abutment to position the contact supports with respect to the reed and frame in order to bring the contact points into proper alinement and also to space the edges of holes 31 and 38 in the contact support bases from the securing 35 screws 39 which pass therethrough. The general vibratory motor structure described above forms no part of the present invention but is described and claimed in prior Patent No. 2,072,578, issued March 2, 1937 on a copending 40 application filed by Edward L. Barrett and Max J. Manahan.

An improved and simplified supporting structure has been provided for the driving contacts 14 and 15 which may be incorporated with the 45 remainder of the vibrator structure without materially affecting the arrangement of the parts or method of assembly. In general, this supporting arrangement preferably includes a sheet metal supporting finger which is disposed in 50 perposed relation with respect to the supporting fingers for the main circuit controlling contacts, whereby a compact, readily assembled stack of laminations or parts is had. Thus, in the preferred construction illustrated one of the driving contacts 14 is carried by sheet metal supporting finger 40, being secured thereto by a thin, light, metal spring 41 which is riveted adjacent its lower end to the supporting finger. This supporting finger 40 is provided with a base 55 portion 42 having a terminal lug 43 thereon, as well as assembly lugs 44. These assembly lugs are disposed in alinement with the assembly lugs 35 and 36 on the supporting fingers 29 and 30 so as to facilitate accurate alinement of the parts 60 during assembly. Enlarged holes 45 are also provided on the base portion 42 of the supporting finger 40. A cooperating driving contact 15 is carried by the reed 16 and may be mounted on the supporting member 27 which carries the main 65 circuit controlling contact 13. A pin 46 made

of aluminum, brass or other light weight material which will not interfere with the vibratory movement of the reed 16 projects laterally from the upper end of the supporting member 27 and the contact point 15 is secured to this pin. The 5 inner end of the pin 46 is of a reduced diameter and projects through a registering hole in the support 27. The driving contacts 14 and 15 illustrated are preferably made of palladium-silver alloy and the contact 15 is welded to the 10 pin 46.

In assembling the parts of the vibratory motor device described above, insulating spacers 47 to 52 inclusive, made of sheet mica or the like are interposed between the various adjacent elements in the relation shown in Fig. 3, in order to electrically insulate the same. The reed 16 and contact supporting fingers 29, 30 and 40, together with their associated insulating spacers, are secured in position on the lower end member 20 of the frame 18 by the screws 39 which pass through alined holes therein. A metal spacer 53 is provided at one end of the stack to prevent scoring of adjacent insulating spacer by the heads of the screws, and a similar member 25 54 is provided at the other end of the stack, having tapped holes 55 therein in which the ends of the screws 39 are threaded. Metal spacers 56 are provided between the various elements of the stack in order to space the contact points the 30 desired distance apart.

In accordance with one aspect of the present invention, an improved form of actuating winding is preferably provided for the electromagnet 17 which is particularly adapted to minimize arcing between the associated driving contacts 14-15. In general, this improved actuating winding includes a wire disposed in a coil in the usual manner, the wire being provided with an electrical conductive sheath surrounding the 40 same and insulated therefrom substantially throughout its length. There are probably several factors which theoretically contribute to the improved result attained when such an arrangement is utilized. Thus, capacitance between the 45 core of the wire and its insulated conductive sheath aids in suppressing the arcing at the driving contacts and in addition the eddy currents and other losses due to the sheath aid in attaining the desired result. By the use of such 50 an arrangement, a comparatively heavy current flow through the electromagnet winding may be had for starting the reed in its vibratory movement, but after this operation has been initiated the sheath apparently acts to reduce the flow of 55 current at the instants at which the driving contacts open and close so as to minimize the arcing therebetween.

It has been found that an effective electrical 60 conductive sheath for the wire of the electromagnet winding may be had by treating the insulating covering of a standard form of insulated wire in the manner hereinafter set forth. One standard commercial form of fine copper wire suitable for use in such a device has a coating 65 of insulating enamel thereon, which is in turn surrounded by a serving or covering of textile material such as cotton or silk. Thus, in the conductor shown in Fig. 5, a fine copper wire 57 has a coating of insulating enamel 58 and a serving 70 of cotton strands 59 thereon. The conductive sheath may be readily formed by filling the interstices of the textile covering with electrical conductive material. It has been found that a good sheath is formed by impregnating a cotton 75

serving on such a wire with colloidal graphite. This impregnation may be effected by dipping the wire in a dispersion of colloidal graphite before the wire is wound in the form of a coil.

The particular electromagnet 17 illustrated is provided with a winding 60 made of a fine copper wire surrounded substantially throughout its length by a conductive sheath formed from a cotton serving impregnated with colloidal graphite as described above. The wire is wound on a spool 61 of insulating material which may be slipped over the pole piece 23. Although such a sheath formed from textile material impregnated with graphite has a resistance which is comparatively high with respect to the resistance of the associated copper wire, this effect is not detrimental in that the adjacent turns of the winding are disposed in close contact so that the resistance across the surface of the coil is low as compared to the resistance from one end to the other of the sheath. In addition, a sleeve 62 of copper or other conductive material may be slipped over the core of the spool 61 so as to form a further low resistance path between adjacent turns of the sheath which it contacts. One end of the wire in the coil 60 is preferably connected to the sheath so that a definite potential relation thereto will be had.

The vibratory motor device described above is preferably assembled with a supporting means which includes an enclosing casing 63 in the form of an elongated cup-shaped container having an open end. This open end of the container is closed by a disk of insulating material 64 carrying suitable contact prongs 65 connected to the various elements of the vibratory motor. A resilient support for the motor within the casing is formed by sponge rubber blocks 66 and 67. The block 66 is generally disk-shaped and receives the lower end of the motor. The upper end of the motor is surrounded by cup-shaped block 67.

The wiring diagram Fig. 4 illustrates one application of the vibratory motor device in which the main circuit controlling contacts 10-11 and 12-13 serve to periodically connect the storage battery 68 to the respective sections 69 and 70 of the primary winding of the transformer 71. The operation of this circuit is initiated by the closure of a starting switch 72 which connects one terminal of the electromagnet actuating winding 60 to one terminal of the battery 68 through conductors 73 and 74, switch 72 and conductors 75. The other terminal of the actuating winding 60 is connected to the other terminal of the storage battery through conductor 76, the normally closed driving contacts 14-15, reed 16 and conductor 17. Upon the completion of this circuit, current flows from the battery 68 through the actuating winding 60 of the electromagnet so that the armature 25 is attracted from its idle position in which it is eccentrically disposed with respect to the pole piece 23, thus swinging the reed 16 to the left (as viewed in Fig. 2) and closing the contacts 10-11. This swinging movement of the reed also opens the driving contacts 14-15, thereby deenergizing the electromagnet winding 60. The closure of the main circuit controlling contacts 10-11 completes a circuit for section 69 of the transformer winding. Thus, one terminal of this transformer section is permanently connected to the battery 68 through conductor 73 while the other terminal thereof is connected to the opposite terminal of the battery through the conductor 78, contacts 10-11,

reed 16 and conductor 17. Since the electromagnet has been deenergized, the reed 16 will swing back, opening the contacts 10-11 and again closing the driving contacts 14-15. The return impulse of the reed is sufficient, however, to close the second pair of main circuit controlling contacts 12-13 in its return movement so as to complete a circuit for a second section 70 of the transformer primary winding. One terminal of this section is permanently connected to a terminal of the battery 68 through conductor 73, while the opposite terminal is connected to the second terminal of the battery through a conductor 79, contacts 12-13, reed 16 and conductor 17. This cycle of movement of the reed 16 is repeated and continued with great rapidity so that impulses of direct current flow through the transformer primary winding sections 69 and 70. These impulses of current induce an alternating current in the transformer secondary winding which may be rectified and utilized in a radio receiving set or the like. The preferred construction illustrated, in which all of the various contacts are disposed in alignment with the aperture 24 in the reed 16 permits the latter to swing with a wide amplitude of movement without impediment from the contacts disposed on its opposite sides. Also the time efficiency is high, that is the main circuit controlling contacts remain closed during a comparatively large portion of each cycle of movement of the reed. It is particularly important that the reed have a large amplitude of free movement when an improved electromagnet actuating winding of the type described is utilized since a heavy initial impulse is given to the reed at starting.

Although a preferred embodiment of the invention has been illustrated and described in some detail, there is no intention to thereby limit the invention to such a preferred embodiment but, on the other hand, the appended claims are intended to cover all modifications within the spirit and scope of the invention.

I claim as my invention:

1. In a vibratory motor, an actuating electromagnet including an electrically conductive wire disposed in the form of a coil, means including a pair of cooperating make and break contacts for periodically connecting said coil to a source of current, and means including a conductive sheath disposed about said wire and insulated therefrom substantially throughout its length for minimizing arcing at said contacts.

2. In a vibratory motor, an actuating electromagnet including an electrically conductive wire disposed in the form of a coil, means including a pair of cooperating make and break contacts for periodically connecting said coil to a source of current, a coating of insulation on said wire, a covering of textile material on said insulation, both said coating and said covering extending substantially throughout the length of said wire in said coil, an electrically conductive material filling the interstices in said textile covering to form a conductive sheath for said wire, the adjacent turns of said coil being disposed in contacting relation.

3. In a vibratory motor, an actuating electromagnet including an electrically conductive wire disposed in the form of a coil, means including a pair of cooperating make and break contacts for periodically connecting said coil to a source of current, a coating of insulation on said wire, a covering of textile material on said insulation, both said coating and said covering extending

substantially throughout the length of said wire in said coil, said covering being impregnated with colloidal graphite to form a conductive sheath for said wire, the adjacent turns of said coil being disposed in contacting relation.

4. In a vibratory motor, an actuating electromagnet including an electrically conductive wire disposed in the form of a coil, means including a pair of cooperating make and break contacts 10 for periodically connecting said coil to a source of current, and means including a conductive sheath disposed about said wire and insulated therefrom substantially throughout its length for minimizing arcing at said contacts, the adjacent 15 turns of said coil being disposed in contacting relation thereby forming a low resistance path through adjacent contacting portions of said sheath from end to end of the coil.

5. In a vibratory motor, an actuating electromagnet including an electrically conductive wire disposed in the form of a coil, a cantilever vibratory reed, an armature carried by the free end of said reed in operative relation with said electromagnet, means including a pair of cooperating make and break contacts actuated by said reed in the vibratory movement thereof for periodically connecting said coil to a source of current, and means including a conductive sheath disposed about said wire and insulated

therefrom substantially throughout its length for minimizing arcing at said contacts.

6. In a vibratory motor, an actuating electromagnet including an electrically conductive wire disposed in the form of a coil, a cantilever vibratory reed, an armature carried by the free end of said reed in operative relation with said electromagnet, means including normally open contacts disposed on opposite sides of said reed and actuated thereby for periodically opening 10 and closing associated circuits, means including a pair of cooperating normally closed make and break contacts actuated by said reed in the vibratory movement thereof for periodically connecting said coil to a source of current, and 15 means including a conductive sheath disposed about said wire and insulated therefrom substantially throughout its length for minimizing arcing at said normally closed contacts.

7. In a vibratory motor, an actuating electromagnet including an insulated electrically conductive wire disposed in the form of a coil, means including a pair of cooperating make and break contacts for periodically connecting said coil to a source of current, and means including a mass 20 of conductive material interposed in the interstices of said coil of insulated wire between individual turns thereof for minimizing arcing at 25 said contacts.

EDWARD L. BARRETT.
